Primary Examiner — Ricky Pham(74) *Attorney, Agent, or Firm* — Foley & Lardner LLP(57) **CLAIM**

We claim the ornamental design for a cooking pot, as shown and described.

DESCRIPTION

FIG. 1 is a perspective view of a cooking pot according to our new design;

FIG. 2 is a right side view of the cooking pot shown in FIG. 1; FIG. 3 is a left side view of the cooking pot shown in FIG. 1; FIG. 4 is a front view of the cooking pot shown in FIG. 1; FIG. 5 is a rear view of the cooking pot shown in FIG. 1; FIG. 6 is a top view of the cooking pot shown in FIG. 1; and, FIG. 7 is a bottom view of the cooking pot shown in FIG. 1. Broken lines in the drawings are for illustrative purposes only and form no part of the claimed design.
